UNITED STATES PATENT OFFICE

GEORGE GOODLINE, OF PHILADELPHIA, PENNSYLVANIA, ASSIGNOR TO GEORGE CROMPTON, RANDOLPH CROMPTON, EDWARD D. THAYER, AND WILLIAM B. SCOFIELD, OF WORCESTER, MASSACHUSETTS, DOING BUSINESS AS CROMPTON-THAYER LOOM COMPANY, OF WORCESTER, MASSACHUSETTS, A FIRM.

TAKE-UP MECHANISM FOR LOOMS.

No. 797,573.

Specification of Letters Patent.

Patented Aug. 22, 1905.

Application filed February 23, 1905. Serial No. 246,827.

To all whom it may concern:

Be it known that I, GEORGE GOODLINE, a citizen of the United States, and a resident of Philadelphia, in the county of Philadelphia and State of Pennsylvania, have invented an Improvement in Take-Up Mechanism for Looms, of which the following description, in connection with the accompanying drawings, is a specification, like letters on the drawings representing like parts.

This invention has for its object the production of a take-up for use more especially in connection with looms for weaving silk and delicate fabrics or the like. Heretofore difficulty has been experienced in keeping the silk fabric stretched or smoothed and free from creases on its way to the take-up roller, and different appliances have been used in the nature of ribs, &c., that serve to smooth out or stretch the fabric from its median line toward the selvages. Usually, also, the fabric has been passed over a roller sustained on the breast-beam of the loom. I have found that I may smooth out and prevent wrinkles from being formed in the fabric and going onto the usual cloth-receiving roller by drawing both sides of the fabric over a plurality of smooth stationary surfaces located between the sand or take-up roll and the usual cloth-receiving roller. The stationary bars or rollers referred to may and will preferably be composed of wood.

Figure 1, in section on the line x , Fig. 2, shows a sufficient portion of a loom embodying my improvements to enable my invention to be understood. Fig. 2 is a front end view of the loom shown in Fig. 1, the web-protector being broken out. Fig. 3 shows in two views a modified form of stationary bar or roll to illustrate another way of restraining the rotation of the bar or roll.

The loom-frame A, the crank-shaft A', sustained in suitable bearings on said frame, the lay-connecting rods A², the lay A³, pivoted at A⁵ and having a beam A⁴ and a reed, the take-up or sand roll A², and the cloth-receiving roller or device A⁶ are and may be all as usual. The breast-beam B, herein shown as composed of wood, is shaped at its outer side to present a curved surface.

The woven web α is led from the front of the

breast-beam down under a revolving weight-roller A', thence over and under a take-up or sand roll A² of larger diameter, the fabric or web on its way between the sand-roll and the cloth-receiving roller A⁶ being led over and across a plurality of stationary rolls or bars A³ A⁴ A⁵, carried in levers d, shown as of elbow shape, loosely pivoted on a rod d', held by set-screws d² on a frame d³ suitably bolted at d⁴ to the framework, the short arms of said levers having connected with them springs d⁵, that act to draw the fabric about said sand-roll A² and take up any slack in the fabric. The rolls or bars shown present curved surfaces that contact with opposite sides of the fabric, and said rolls or bars are located quite close together, as thereby the fabric is better smoothed or ironed and kept under a more even and uniform tension, and the liability of wrinkles due to uneven strain on the fabric is less than were the rolls or bars widely separated.

The roll A', the take-up or sand roll A², and the cloth-receiving roller A⁶ are sustained in two side frames d³, suitably secured at their lower ends to the loom sides and at their upper ends to the under side of the breast-beam. One side frame has a stud b², that receives over it loosely the hub b³ of a ratchet-wheel b⁴, said hub having a pinion b⁵. This ratchet-wheel may be moved intermittently by any means usual in looms for this purpose—as, for instance, a pawl b⁶, connected with a lever b⁷, moved by the lay. The pinion b⁵ engages a toothed gear c, having a connected pinion c', that in turn engages a toothed gear c², fast on one of the journals of the sand-roller A². The opposite journal of said roll has a sprocket-wheel e, over which is passed a sprocket-chain e', that in turn engages a sprocket-wheel e² on one end of the cloth-receiving roller. The sprocket-wheel e is clamped securely in working position on the journal of the sand-roll A² by suitable nuts, and by loosening said nuts the wheel e may be disconnected from said roll, as when it is desired to draw the fabric off the cloth-receiving roller, at which time the roll must turn freely.

The bars or rolls A³ A⁴ A⁵ will be restrained from rotation as the web is drawn over the same by any suitable means, the means shown in Fig. 1 being screws extended through the

levers *d* and entering the ends of the bars snugly, thus restraining the rotation of said bars between said levers. If desired, however, each bar or roll may have a projection *p* at each end, said projection being other than round, and said projection may enter ways between flanges *p'*, forming parts of the rolls, as shown in Fig. 3.

I have arranged a web-protector *B'* in front of the breast-beam, it serving to prevent the weaver from coming in contact with the woven web.

Having fully described my invention, what I claim as new, and desire to secure by Letters Patent, is—

1. In a loom, a breast-beam, a cloth-receiving roller and a sand or take-up roll to which the cloth being woven is led, combined with a plurality of stationary bars arranged between said sand or take-up roll and said cloth-receiving roll and between and about which the woven cloth is drawn and ironed by the contact of said cloth at both sides with said bars on its way to the cloth-receiving roller.

2. In a loom, a revolving take-up roller, a plurality of non-rotatable devices having arc-

shaped surfaces over which the fabric passes prior to being wound on the take-up roll, a movable frame sustaining said devices, and a yielding device acting to retain said frame in its operative position.

3. In a loom, a breast-beam, a sand or take-up roller, a weight-roller acting on the cloth between said breast-beam and sand or take-up roller, a cloth-receiving roller and a movable frame sustained in front of said sand or take-up roller and provided with a plurality of stationary bars over which the cloth is led after it leaves the take-up or sand roller on its way to said cloth-receiving roller, said stationary bars acting upon opposite sides of the cloth and ironing and smoothing the cloth to remove any wrinkles therefrom as the cloth approaches the receiving-roll to be wound thereon.

In testimony whereof I have signed my name to this specification in the presence of two subscribing witnesses.

GEO. GOODLINE.
